UNITED STATES PATENT OFFICE.

JOSEPH ANTHONY PARRELLA, OF WASHINGTON, DISTRICT OF COLUMBIA.

PEN-EXTRACTOR.

1,274,760.

Specification of Letters Patent. Patented Aug. 6, 1918.

Application filed March 22, 1918. Serial No. 223,984.

To all whom it may concern:

Be it known that I, JOSEPH A. PARRELLA, a citizen of the United States, residing at Washington, in the District of Columbia, 5 have invented certain new and useful Improvements in Pen-Extractors, of which the following is a specification.

My invention relates to pen extractors.

An important object of the invention is 10 to provide a device of the above mentioned character, so constructed that a positive or powerful grip may be obtained upon the pen point, without liability of the fingers being soiled by contact with the pen point.

15 A further object of the invention is to provide a device of the above mentioned character, which is simple in construction, inexpensive to manufacture, strong, and highly convenient in use.

20 Other objects and advantages of the invention will be apparent during the course of the following description.

In the accompanying drawings, forming a part of this specification, and in which 25 like numerals are employed to designate like parts throughout the same,

Figure 1 is a perspective view of a different form of the invention, and,

Fig. 2 is a side elevation of the same.

30 In the drawings, wherein for the purpose of illustration is shown a preferred embodiment of my invention, the numeral 5 designates a U-shaped body portion or member, formed of suitably stiff and resilient metal. 35 The U-shaped member embodies oppositely arranged arms 6, as shown. The oppositely arranged arms 6 have their material at their forward or free ends bent inwardly at a right angle, forming inwardly projecting lateral 40 extensions 7. The extensions 7 are preferably tapered, decreasing in width inwardly.

Jaws 10 are formed upon the lateral extensions 7, and are disposed at a right angle thereto, and parallel with the arms 6. The 45 jaws 10 have their inner faces serrated or milled. The jaws 10 project inwardly with relation to the arms 6.

The operation of the device is as follows:

The U-shaped body portion 5 may be held

in the right hand between the thumb and 50 index finger, which engage the arms 6. The pen holder is held in the left hand, and moved toward the device until the pen point is arranged between the jaws carried by the lateral extensions 7. Pressure is now applied to the arms 6 whereby the jaws are brought into positive clamping engagement 55 with the pen point. The device is now moved longitudinally away from the pen holder and extracts or removes the pen point 60 therefrom. Particular attention is called to the perpendicular arrangement of the lateral extensions 7 with relation to the arms 6, which permit of a positive or powerful 65 clamping action being had with the pen point, such action occurring principally at the heels of the jaws. By the provision of the lateral extensions, the fingers are spaced a substantial distance from the pen point and therefore prevented from being soiled 70 by contact with the pen point.

It is to be understood that the form of my invention herewith shown and described is to be taken as a preferred example of the same, and that various changes in the shape, 75 size, and arrangement of parts may be resorted to, without departing from the spirit of my invention or the scope of the subjoined claim.

Having thus described my invention what 80 I claim is:

A pen extractor, comprising a U-shaped body portion formed of suitably stiff and resilient metal and having oppositely arranged substantially flat arms; inwardly 85 projecting extensions formed upon the ends of the substantially flat arms by bending the material of said arms, said extensions being disposed perpendicular to said arms and tapered and decreasing in width inwardly, 90 said extensions being of substantial length whereby the fingers are permanently held out of contact with the pen; and serrated jaws formed upon the inner ends of the extensions. 95

In testimony whereof I affix my signature.

JOSEPH ANTHONY PARRELLA.
